FIG. 1

FIG. 2

UNITED STATES PATENT OFFICE.

HEIN DE VRIES, OF HOOD, CALIFORNIA.

DESIGN FOR A DISH.

45,926.

Specification for Design.

Patented June 16, 1914.

Application filed March 23, 1914. Serial No. 826,826. Term of patent 3½ years.

To all whom it may concern:

Be it known that I, HEIN DE VRIES, a subject of the Queen of the Netherlands, residing at Hood, in the county of Sacramento and State of California, have invented a new, original, and ornamental Design for Dishes, of which the following is a specification, reference being had to the accompanying drawing, forming part thereof.

Figure 1 is a perspective view of a dish illustrating my design and Fig. 2 is a sectional view through the handle of the dish.

I claim:—

The ornamental design for a dish, as shown.

HEIN DE VRIES.

Witnesses:

FRANCIS M. WRIGHT,
D. B. RICHARDS.
